J. G. GIBSON

WATER GRATE

Original Filed July 5, 1923

Inventor
John G. Gibson

Attorney
William J. Jackson

UNITED STATES PATENT OFFICE.

JOHN G. GIBSON, OF VENTNOR, NEW JERSEY.

WATER GRATE.

Original application filed July 5, 1923, Serial No. 649,487. Divided and this application filed October 24, 1924. Serial No. 745,548.

This invention, generally stated, relates to steam and hot water boilers employing forced or induced draft and has more particular relation to the providing of certain new and novel sectional hollow grates therefor which may be formed integral with the water-legs of a boiler section at the time of manufacture of the boiler or which may be installed in existing boilers without effecting change in the construction thereof. Other and further objects relate to the provision of general details of construction and in the arrangement and combination of parts hereinafter set forth.

15 The invention consists of the novel structure hereinafter described and finally claimed.

The nature, characteristic features and scope of the invention will be more fully understood from the following description taken in connection with the accompanying drawings forming part hereof, and in which:

20 Fig. 1 is a top view partly sectioned of a pair of detachable grate-bars.

Fig. 2 is a view in section showing a "repair" element in position in lieu of the flange 17 which has broken off.

25 Fig. 3 is a fragmentary view illustrating the grate-bar as shown in Figs. 1 and 2 formed integral with the water-leg of a boiler section.

For the purpose of illustrating my invention I have shown in the accompanying drawings one form which is at present preferred by me, since the same has been found in practice to give satisfactory and reliable results, although it is to be understood that the various instrumentalities of which my 30 invention consists can be variously arranged and organized and that my invention is not limited to the precise arrangement and organization of the instrumentalities as herein shown and described. This case is a division of application Ser. No. 649,487.

In the water-grate claimed in my Patent Number 1,366,377 dated January 25, 1921, use is made of removable, tubular sections having perforated domes. In the present 35 instance these sections may be omitted or used in certain instances and the grooves of adjacent grate-bars form tubular channels for the passage of air to the grate surface. The grooves, however, do not extend through the top of a grate-bar as shown in

my said patent and while the flanges at the lower end of the grooves may remain it is preferable in some cases to omit same. With the exception of these changes the general arrangement of grate-bar is similar to that disclosed in patent aforesaid.

40 Referring now to the drawings, 10 designates a grate-bar which is hollow for the circulation of water therethrough as is well understood in the art. Each side wall of a grate-bar 10 is vertically grooved from the bottom thereof to within a short distance of the top thereof. These grooves which may be of any desired shape are spaced apart and are designated 11. The

45 top wall of a grate-bar overhangs the grooves 11' of a companion grate-bar throughout its extent. In other words the overhang is continuous. The opposite

50 grooved face of each grate-bar is provided with horizontally disposed, spaced ribs 12 adapted to co-actively engage with said recessed portions 13 whereby adjacent or abutting grate-bars may be interlocked. These recessed and ribbed portions form

55 overlapping parts to preclude air seeping up between adjacent grate-bars, or in other words all air must pass up through the apertures of the ledges, to be evenly distributed, as before described. In practice

60 cement or the like may be applied between the adjacent faces of grate-bars. The side walls 14 of each grate-bar are shaped to follow the curves of the grooves 11 so that

65 approximately the same thickness of metal is present throughout a grate-bar to provide for uniformity of cooling surface. The thickness of the over-hung portions is of approximately the same thickness as the

70 grate-bar. Each grate-bar is provided upon one side wall with grooves 11', above mentioned, which extend through the grate-bar top in the same manner as those shown in my aforesaid patent. These grooves are

75 recessed or countersunk at their tops as at 15. At their bottoms each set of grooves are provided with flanged parts 16. The

80 grate top upon that side provided with grooves 11 is provided with laterally disposed flanged parts 17 which not only overhang said grooves 11 but are further extended to seat within the recessed or countersunk parts 15 of grooves 11' of an adjacent grate-bar. These flanges 17 are semi-circular, as are the recessed parts 15, and

are apertured as at 18 for the passage of air to the grate-surface. A particular advantage derived from this type of construction is that if a flanged part 17 fractures as at 19, see Fig. 2, one of the hollow members with perforated domes as disclosed in my aforesaid patent and designated in Fig. 2, as 20, may be introduced within the channel as formed by grooves 11-11' and seated upon flanged parts 16. This avoids substituting a new grate-bar. The above described type of grate-bar may be cast integral with a water-leg 19' of a boiler, as shown in Fig. 3.

15 It will now be apparent that I have devised a novel and useful construction which embodies the features of advantage enumerated as desirable in the statement of the invention and the above description and while 20 I have in the present instance shown and described the preferred embodiment thereof which has been found in practice to give satisfactory and reliable results, it is to be understood that the same is susceptible of 25 modification in various particulars without departing from the spirit or scope of the invention or sacrificing any of its advantages.

What I claim is:

1. In a grate construction of the character 30 stated a plurality of hollow grate-bars arranged side by side the meeting faces of said grate-bars being provided with registering, vertical grooves cooperating to provide air ducts, the top wall of a grate-bar adjacent one set of grooves being recessed and bevelled and the top wall thereof overlying the opposed set of grooves and flanged to seat within the recessed part of a companion

grate-bar, the flanged part being bevelled and apertured in communication with registering grooves. 40

2. In a grate construction of the character stated a plurality of hollow grate-bars arranged side by side, the meeting faces of said grate-bars being provided with registering, vertical grooves cooperating to provide air ducts, the top wall upon one side of a grate-bar overlying one set of grooves and having a plurality of countersunk, bevelled spaced portions and the top wall of the opposite side of the grate bar being provided with a plurality of laterally extended spaced flanges shaped to seat with said countersunk portions of a companion grate-bar, said flanged parts being apertured in communication with said registering grooves. 50

3. In a grate construction of the character stated a plurality of hollow grate-bars arranged side by side, the meeting faces of said grate-bars being provided with registering, vertical grooves cooperating to form air ducts, the top wall of a grate-bar adjacent one set of grooves being formed upon an arc of a circle and recessed and the top wall thereof overlying the opposed set of grooves and flanged upon an arc of a circle to seat within the recessed part of a companion grate-bar, the flanged part being apertured in communication with registering grooves one side wall of each grate-bar being horizontally recessed and the opposite side wall being ribbed for engaging a recessed wall of a companion grate-bar. 60

In testimony whereof, I have hereunto signed my name.

JOHN G. GIBSON.
